UNITED STATES PATENT OFFICE.

GEORGE S. GALLAGHER, OF NEW YORK, N. Y., ASSIGNOR TO ZILLIAH B. GALLAGHER, EMMA G. GALLAGHER, AND HARRY F. GALLAGHER, OF SAME PLACE.

SMOKE-CONSUMING DEVICE FOR FURNACES.

SPECIFICATION forming part of Letters Patent No. 667,126, dated January 29, 1901.

Application filed June 9, 1900. Serial No. 19,666. (No model.)

To all whom it may concern:

Be it known that I, GEORGE S. GALLAGHER, a citizen of the United States, residing at the borough of Manhattan, in the city, county, and State of New York, have invented an Improvement in Smoke-Consuming Devices for Furnaces, of which the following is a specification.

My present invention is designed as an improvement upon the device shown and described in my former application for Letters Patent, Serial No. 1,039, filed January 11, 1900, allowed April 30, 1900. In the device of said application flues were made in the side and front walls and bridge-wall of the furnace, with connecting-throats and a series of openings. Pipes for air were placed in said flues and injector-nozzles therefrom in the series of openings, and in the action of said device the smoke and unconsumed gases were drawn off the fire and forced back with an abundant supply of air to be consumed in the combustion-chamber under the boiler. In my present invention I continue the system of my aforesaid application and provide flues in the opposite side or face of the bridge-wall and in the side walls of the furnace beyond and back of the bridge-wall, and I throw over an arch beneath the boiler beyond and back of the bridge-wall, and said flues are provided with series of openings, with pipes for air and injector-nozzles in the series of openings. The products of combustion are obliged to pass rearward from the fire beneath the boiler over the bridge-wall and down beneath the arch, and any unconsumed or imperfectly-consumed gases or smoke passing over the bridge-wall meet the air forced from the flues and nozzles between the bridge-wall and the arch, where the same are consumed, so that a perfect combustion results.

In the drawings, Figure 1 is a longitudinal section through the lower part of the boiler and walls from the front rearward, and Fig. 2 is a sectional plan of the same below the line of the boiler.

The side walls *a a*, the front wall *b*, and the

bridge-wall *c*, together with the foundation thereof, are preferably built, as usual, of brick, and the grate-bars *d* are supported in any desired manner. The front wall of the furnace is provided with fuel-doors *2* and ash-doors *3*, and the ash-pit *e* is, as usual, below the grate-bars *d*. I prefer, as set forth in my aforesaid application, to employ flues *f g*, and *h*, running horizontally and lengthwise of the walls, and to employ throats, as *g' h'*, in the side walls and as *f'* in the front wall above the level of the grate-bars and connecting with the flues *f g*, and *h*, and in said flues *f g h* I place a pipe for air under pressure, which pipe is provided with injector-nozzles projecting through series of openings connecting the flues with the combustion-chamber. In my present improvement a main pipe *k* enters from the rear about midway between the side walls above the foundation and passes up into the bridge-wall and is provided with lateral horizontal branches *k'*, extending in opposite directions through the flue *i* of the bridge-wall. The ends of the pipe *k* are provided with T-couplings, and from these the longitudinal branch pipes *k*² extend forward through the flues *h* and *g*, one of said pipes passing around and through the front flue *f*. The pipes *k*² are provided with injector-nozzles extending out through series of openings, as shown in the drawings and as described in my aforesaid application.

The flue *i* in the bridge-wall is preferably provided with one or more throats *i'*, performing a similar office to the throats *f' g'*, and *h'* of my said application and for the purpose of drawing the smoke and unconsumed gases off the fire and forcing the same, with an abundant supply of air, back into the combustion-chamber to be consumed between the bridge-wall and the front and side walls beneath the boiler. In my present improvement the bridge-wall is provided with a series of openings extending in both directions toward both faces of the said wall and connecting the flue *i* with the chambers at either side of the wall, and the branch pipes *k'* are

provided with series of injector-nozzles projecting into the said openings.

An arch *n* is provided or thrown over beneath the boiler and rearward of the bridge-

- 5 wall *c*, and between the arch and the bridge-wall in the side walls *a* I provide flues *l m* for the longitudinal rearward branch pipes *k³*, that connect with the couplings of the pipes *k'*, and these flues *l m* are also provided with
10 a series of openings for injector-nozzles connected to the pipes *k³*, so that air under pressure forced through the pipe *k* passes through pipes *k' k² k³* and all the injector-nozzles connected therewith. From some of the nozzles
15 the air passes into the combustion-chamber and from thence into the chamber between the bridge-wall and the arch. The operation of the device is similar to that set forth in
20 my aforesaid application and as hereinbefore intimated. The products of combustion from the main chamber under the boiler between the side and front walls and the bridge-wall pass over the bridge-wall and down beneath the arch to the rear of the boiler, and should
25 there be any unconsumed gases or smoke or partially consumed gases passing over the bridge-wall the same are met with an abundant supply of air in the chamber beneath the boiler between the side walls, the bridge-
30 wall, and the arch with the object of fully consuming the said gases or smoke and effecting a perfect combustion, so that none of the units of heat are wasted, but all are utilized.

- 35 The flues *l m* and the series of openings connecting the same with the chamber back of the bridge-wall are formed for the purpose of holding the pipes *k³* and the injector-nozzles connected therewith. The throat or
40 throats *i'* communicate with the flue *i* through the bridge-wall and the smoke and unconsumed gases passing through these throats might appear to pass freely in opposite directions into both chambers through the series of openings, to overcome which I may
45 find it advantageous to partially or wholly close off the possibility of the said products of combustion and smoke passing rearward into the chamber behind or back of the
50 bridge-wall, and so compel the same to be entirely thrown forward over the grate-bars and fuel.

- The injector-nozzles projecting from the pipes *k' k²* through the series of openings surrounding the fire-chamber may by preference be of larger area, and consequently greater capacity than the injector-nozzles projecting from the pipes *k' k³* through the series of openings on three sides of the chamber between the arch, sides, and bridge-wall, so as to insure the smoke and gases being drawn off the fire and projected with an abundant supply of air into the chamber over the fire, as an abundant supply of air is more essential in

the fire-chamber than rearward of the bridge-wall.

I claim as my invention—

1. The combination in a smoke-consuming furnace with flues placed horizontally in the walls, and series of openings connecting the same with the fire-chamber and pipes for air under pressure in said flues and injector-nozzles in said openings, of an arch beneath the boiler and rearward of the bridge-wall, flues in the side walls between the bridge-wall and the arch, and series of openings connecting the said flues with the chamber between the bridge-wall and the arch, and pipes for air under pressure in said flues and injector-nozzles in said openings, substantially as set forth.

2. The combination in a smoke-consuming furnace with flues placed horizontally in the side walls, series of openings connecting the same with the chamber above the grate-bars and pipes for air under pressure in said flues and injector-nozzles in said series of openings, of a bridge-wall having a flue passing longitudinally of the same and series of openings connecting the same with the chamber above the grate-bars and the chamber rearward of the bridge-wall, a pipe for air under pressure passing through the said bridge-wall flue and injector-nozzles extending therefrom through both series of openings, an arch beneath the boiler rearward of the bridge-wall, flues in the side walls between bridge-wall and the arch and series of openings connecting the said flues with the chamber between the bridge-wall and arch, pipes for air under pressure in said flues and injector-nozzles extending from said pipes through said openings, substantially as set forth.

3. The combination in a smoke-consuming furnace, with the side walls, the bridge-wall and an arch beneath the boiler and rearward of the bridge-wall and the grate-bars whereby a combustion-chamber is formed above the grate-bars and another chamber between the bridge-wall and the arch, of flues in the side walls and in the bridge-wall, and series of openings connecting said flues with both of said chambers, a pipe for air under pressure coming up through the bridge-wall with branches extending in both directions through the flue of the bridge-wall into the side walls and with other branches extending both forward and rearward through the flues in the side walls, and injector-nozzles extending from said pipes into said series of openings whereby air is forced from said pipes simultaneously into both chambers of the furnace, substantially as set forth.

4. The combination in a smoke-consuming furnace with flues placed horizontally in the walls, and series of openings connecting the same with the fire-chamber and pipes for air under pressure in said flues and injector-noz-

zles in said openings, of an arch beneath the boiler and rearward of the bridge-wall, pipes for air under pressure in the side walls and in the bridge-wall connected to and extending from the aforesaid pipes, and injector-nozzles extending from said pipes in the side walls and from the pipes in the bridge-wall for delivering air under pressure into the

chamber rearward of the bridge-wall and between the same, the arch and the side walls, substantially as specified.

Signed by me this 5th day of June, 1900.

GEORGE S. GALLAGHER.
